UNITED STATES PATENT OFFICE.

JOHN T. MELSON, OF LAUREL, DELAWARE, ASSIGNOR OF ONE-EIGHTH TO WILLIAM E. VALIANT, ONE-EIGHTH TO ALBERT H. PHILLIPS, AND ONE-EIGHTH TO WILBER P. ELLIS, ALL OF LAUREL, DELAWARE.

PACKAGE-TIE.

1,275,169.

Specification of Letters Patent.

Patented Aug. 6, 1918.

Application filed September 17, 1917. Serial No. 191,787.

To all whom it may concern:

Be it known that I, JOHN T. MELSON, a citizen of the United States, residing at Laurel, in the county of Sussex and State of Delaware, have invented new and useful Improvements in Package-Ties, of which the following is a specification.

This invention relates to package ties or tie fasteners, and the primary object of the same is to provide a simple and inexpensive tie fastener formed of non-corrosive material, preferably wood, and particularly adapted to secure a cord passed about a package, the tie member operating to exert a tension as well as a positive securing action relatively to the cord or binder which is passed around the package to resist accidental loosening or disengagement during transportation of a package, as for instance through the mails. A further object of the invention is to provide a package tie with a locking member having a structure that will permit a ready over-turning movement of the said member and also receive portions of the windings of the cord or binder within the body thereof to provide for a close association of the fastener and cord or binder and to prevent slipping or displacement of the fastener or locking member out of engaging relation with the cord or binder, the tie being easily disengaged by a reverse overturning operation of the fastener or locking member when it is desired to release the cord or binder from the package. A still further object of the invention is to provide a package tie comprising a binder or cord and a fastener or locking member of such construction that it will not cut or readily wear out the said cord or binder and thereby permit repeated use of the improved device in connection with a number of packages with material advantages in the cost of devices of this class.

The invention consists in the construction and arrangement of the tie member or fastener which will be more fully hereinafter described and claimed.

In the drawings:—

Figure 1 is a perspective view of a package showing a binder or cord applied thereto and provided with the improved tie securing or locking member in the first position.

in full lines prior to the overturning movement thereof.

Fig. 2 is a view similar to Fig. 1 showing the binder or cord completely applied to the package and the tie securing or locking member in completely overturned position and diagonally pushed under the crossed portions of the cord or binder.

Fig. 3 is a view similar to Figs. 1 and 2 showing the tie securing or locking member overturned under the crossed portions of the binder or cord and shifted into the final locking position.

Fig. 4 is a detail perspective view of the improved tie securing or locking member.

The numeral 5 represents a cord or binder of any suitable length and diameter having a securing tie or locking member 6 attached to one end thereof and preferably formed of wood shaped to provide the several structural features that will now be described. The securing tie or locking member 6 is of symmetrical contour and comprises oppositely beveled or tapered extremities 7 and 8 with a central transverse recess 9 and central side edge clearance depressions 10 between said extremities. The general marginal contour of the locking member or fastener 6 is rectangular, and the side thereof opposite that having the recess 9 therein is flat as at 11. The extremities 7 and 8 bevel or taper from a central ridge 12 on one side of the member or fastener, the recess 9 being centrally located in said ridge. As clearly shown by Fig. 4, the extremity is longitudinally recessed to form a cord or binder seat 13 with an inner wall 14 following the bevel or taper of said extremity. An opening 15 is bored through said extremity 7 at an angle of inclination close to the wall 14 to receive one end of the cord or binder which is knotted and secured to the member or fastener at this point and passes freely away from the side of the member having the ridge 12 and recess 9.

In applying the binder or cord and the improved fastener or locking member to a package, the tie or locking member is held in the position shown by Fig. 1 with the thumb of the one hand bearing on the extremity 7 to raise or throw out the extremity 8. The binder or cord 5 is then passed com-

pletely around the package in one direction and then crossed over the longitudinal portion of the binder or cord under the center of the fastener or member and wrapped 5 transversely around the package several times, the recess 9 standing over said cross windings and the clearance recesses 10 permitting a ready cross manipulation of the cord or binder without wearing on or cutting 10 the cord, the free extremity of the binder or cord being held taut until the fastener is operated to complete the tie. After the binder or cord 5 has been applied as just explained and as shown by Fig. 1, 15 the fastener is slightly shifted to the left in a diagonal plane and the extremity 7 is lifted or forced outwardly and overturned so that the extremity 8 may be pushed under the crossed cord windings as shown by Fig. 2. When the fastener is overturned, the flat 20 side 11 bears on the package, and to complete the tie the fastener is shifted to the position shown by Fig. 3 with the cross windings of the cord in the seat 12 against 25 the wall 13 to hold the fastener against loose movement. By this operation or overturning movement of the securing tie or locking member, a loop is given to the free extremity of the binder or cord, as at 5^a, 30 and at the same time a positive tension is given to the binder or cord and the package securely fastened or tied without resorting to knots. When it is desired to release the binder or cord, the securing tie or locking 35 member is shifted horizontally to release the cross windings of the cord from the recess 12 and overturned in a reverse direction, or to the position shown by Fig. 1, thereby relieving or relaxing the binder or 40 cord which may then be readily detached by unwinding the same from the package.

The binder or cord 5 is shown in the drawings as being wrapped around the package in a particular manner, for the 45 purpose of illustrating one mode of application thereof. It should be understood, however, that the cord or binder may be wrapped in various ways around a package and the improved fastener or locking member overturned and pushed under the cord or binder for giving a tension to the windings of the cord or binder and preventing 50 accidental loosening of the latter after the fastener is operated to secure the same. It should also be understood that the improved 55 fastener or locking member may be made in various sizes and that the binder or cord may be of different lengths.

One of the advantages of the improved 60 fastener or locking member is that the loose extremity of the cord or binder is not required to be drawn into a binding notch or slot, but on the contrary remains loose and is positively secured in an automatic 65 manner by the overturning of the fastener

or locking member. A further advantage is the coöperative engagement of the fastener or locking member and the transverse windings of the cord or binder and whereby the latter and the fastener or locking member are held against displacement relative to the package and relaxation of the cord or binder and loosening of the package is avoided. A still further advantage is the simplicity and ready application of the cord 70 or binder and the fastener or locking member to a package. A further advantage in the use of the fastener or locking member is the intermediate ridge which is held in engagement with the package and serves to 80 guide the application of the cross or transverse windings of the cord or binder and also to prevent the said windings from slipping backwardly under the fastener, especially when the cord or binder is passed 85 under the extremity 8 of the member to produce said transverse windings.

What is claimed is:

1. A package tie consisting of a locking member to one extremity of which a binder 90 is adapted to be attached, said member having a flat side, and a central transverse ridge on the opposite side, the latter side reversely beveling or sloping off from said ridge toward the ends of the member, the ridge being formed with a fully open recess extending across the member from one side edge to the other, the member being overturned endwise to secure the windings of the binder. 100

2. A package tie consisting of a locking member having one extremity to which a binder is adapted to be attached and the opposite extremity free, the member having one flat side and the opposite side formed with an intermediate ridge extending fully from one side edge to the opposite side edge thereof, the side of the member having the ridge being regularly sloped or beveled in reverse directions from the ridge toward the 110 opposite ends of the member, the ridge having a fully open recess extending centrally thereacross and one sloped or beveled extremity also formed with a longitudinal recess to receive a part of the windings of the 115 binder.

3. A package tie consisting of a locking member having the one side thereof from the center reversely beveled fully to the opposite ends and adapted to have a binder attached 120 to one extremity, the extremity to which the binder is attached being recessed and reduced in thickness to provide a seat for a portion of the windings of the binder.

4. A package tie consisting of a locking 125 member having one extremity to which a binder is adapted to be attached, the member also having the extremity reversely beveled on one side toward opposite ends and intersected by a transverse ridge having an open 130

recess to form a seat which is fully open to receive portions of the binder therein, the side edges of the member having recesses at the opposite terminals of the ridge and intersecting the said seat recess of the ridge.

5. A package tie consisting of a locking member having one extremity to which a binder is adapted to be attached, both extremities of the member on one side being 10 regularly sloped or beveled toward opposite ends and the extremity to which the binder is attached being longitudinally recessed for a portion of its width, the sloped or beveled extremities extending from a central transverse ridge.

15. 6. A package tie, consisting of a locking member having one side flat and the extremities on the opposite side reversely beveled from a central transverse ridge, the one extremity being reduced in thickness for a portion 20 of its width and adapted to have a binder secured thereto, the opposite extremity serving as a fulcrum means for an endwise overturning movement of the mem-

ber, and to facilitate slipping, the extremity 25 serving as the fulcrum means endwise under the binder windings and to laterally move the opposite extremity partially under the said windings.

7. A locking member for a package tie, 30 having a flat side and the opposite side formed with a central transverse recessed ridge from which the extremities are beveled in reverse directions, the one beveled extremity having a longitudinal recess with an 35 inner guard wall and an opening for attachment of a binder thereto, the side edges of the member at the opposite terminals of the recessed ridge having binder engaging depressions.

40 In testimony whereof I have hereunto set my hand in presence of two subscribing witnesses.

JOHN T. MELSON.
